UNITED STATES PATENT OFFICE.

HENRY E. CASWELL, OF JEFFERSONVILLE, OHIO.

MOUTH-SPECULUM.

965,079.

Specification of Letters Patent. Patented July 19, 1910.

Application filed March 10, 1910. Serial No. 548,385.

To all whom it may concern:

Be it known that I, HENRY E. CASWELL, a citizen of the United States, residing at Jeffersonville, in the county of Fayette and State of Ohio, have invented certain new and useful Improvements in a Mouth-Speculum; and I do declare the following to be a full, clear, and exact description of the invention, such as will enable others skilled in the art to which it appertains to make and use the same.

This invention relates to improvements in mouth speculums for dental operations.

One object of the invention is to provide an improved mouth speculum by means of which the cheeks and tongue of the patient may be effectually held out of the way and protected while drilling or operating on the teeth.

Another object is to provide a speculum of this character having arranged therein mirrors whereby the dental operations are greatly facilitated.

With the foregoing and other objects in view, the invention consists of certain novel features of construction, combination and arrangement of parts, as will be more fully described and particularly pointed out in the appended claims.

In the accompanying drawings, Figure 1 is a perspective view of a mouth speculum constructed in accordance with the invention; Fig. 2 is a horizontal section of the same; Fig. 3 is a vertical sectional view of the blades of the speculum, showing a modified form of the same.

Referring more particularly to the drawings, 1 denotes my improved speculum which consists of two disks or blades 2, which may be of any suitable shape and which are here shown and are preferably of oval or elliptical form. These disks or blades 3 are connected together and spaced a suitable distance apart by a connecting bar 3, which is secured to the outer edges of the blades, preferably midway between their ends, as shown.

To the inner edge of the blades, is secured a shank 4, the outer end of which is preferably threaded and which is disposed at the proper angle with respect to the blades for engaging the latter with the cheek and tongue of the patient for the purpose of holding these parts back from the teeth so that access may be had thereto for the purpose of drilling or otherwise operating

thereon. The blades 2 also serve to protect the tongue, cheeks and soft tissues of the mouth from injury by the dental instruments which are being used on the teeth. 60 With the threaded end of the shank, is engaged a handle 5 which may be of any suitable length and which is provided in its outer end with a threaded socket to receive the threaded shank of the tool. 65

If desired, the inner sides of the disks or blades 2 may have arranged therein mirrors 6 by means of which the dental operation may be more readily observed and thereby greatly facilitated. 70

The instrument is reversible and can be used with equal advantage in either side of the mouth and on the upper or lower arch. The use of the instrument is varied and the various uses will appear to the dentist as 75 occasion may require.

From the foregoing description, taken in connection with the accompanying drawings, the construction and operation of the invention will be readily understood without 80 requiring a more extended explanation.

Various changes in the form, proportion and the minor details of construction may be resorted to without departing from the principle or sacrificing any of the advantages 85 of the invention, as defined in the appended claims.

Having thus described my invention, what I claim is:

1. In a mouth speculum, a substantially 90 U-shaped shank, a plurality of oppositely disposed spaced blades mounted on the arms of said shank and a handle detachably connected to said shank at the end of one arm thereof. 95

2. In a mouth speculum, a curved shank, a plurality of oppositely disposed spaced blades mounted over said shank, means formed on said blades for detachably securing mirrors therein and means carried 100 by said shank whereby a handle may be connected therewith.

3. In a mouth speculum a substantially 105 U shaped shank, a disk having a transverse aperture therein mounted on one arm of said shank, a second disk having an aperture therein adapted to be secured to the end of the other arm of said shank, and a handle detachably connected to the opposite end of said shank. 110

4. In a mouth speculum, a substantially U shaped shank having a threaded end por-

tion, a handle adapted to be detachably connected upon said end portion, a pair of spaced oppositely disposed disks secured upon the shank, said shank being adapted to extend through one of said disks, and having its end secured within the other of said disks.

In testimony whereof I have hereunto set my hand in presence of two subscribing witnesses.

HENRY E. CASWELL.
